UNITED STATES PATENT OFFICE.

JOHN T. HUME, OF CHICAGO, ILLINOIS, ASSIGNOR TO HURLEY MACHINE COMPANY, OF CHICAGO, ILLINOIS, A CORPORATION OF ILLINOIS.

VACUUM CLEANER.

Application filed December 1, 1921. Serial No. 519,230.

To all whom it may concern:

Be it known that I, JOHN T. HUME, a citizen of the United States, residing at Chicago, in the county of Cook and State 5 of Illinois, have invented certain new and useful Improvements in Vacuum Cleaners, of which the following is a specification.

My invention relates to improvements in vacuum cleaners, and in some particulars 10 more especially to brush-equipped machines in which a rotary brush, arranged in the nozzle, is driven from the electric motor that also drives the fan. Among the objects of my invention are, betterment of the 15 machine in its brushing functions; improvement of the brush mounting and the brush driving mechanism; attainment of simplicity of construction and ease of assembly, making for cheapness and facility in quantity-manufacture; and utilization of rugged, durable structure throughout, but in an organization facilitating easiest access to 20 and replacement of parts that inherently are subject to wear.

Other and more specific objects of my invention will become apparent from the 25 following description, taken in conjunction with the accompanying drawings, wherein I have shown a single form of construction 30 embodying my invention, for purposes of illustration, although it will be understood that in many particulars changes may be made in the specific embodiment of the invention, and adaptation of features herein- 35 after claimed may be made to embody such features in different particular makes of machines.

In the drawings, Fig. 1 represents a side elevation of a vacuum cleaner embodying 40 my invention, with parts broken away; Fig. 2 is a bottom plan view with a gear-case cover-plate removed; Fig. 3 is a fore-and-aft section approximately on line 3—3 of Fig. 2; Fig. 4 is a transverse section on line 45 4—4 of Fig. 2; Fig. 5 is a section approximately on line 5—5 of Fig. 2; Fig. 6 is a transverse section on line 6—6 of Figs. 2 and 5; Figs. 7, 8 and 9 are sections on lines 7—7, 8—8 and 9—9 of Fig. 2; Fig. 10 is a 50 bottom plan view of the main frame casting; Fig. 11 is a section on line 11—11 thereof; Fig. 12 is a bottom plan view of the brush-frame assembly, and Fig. 13 is an end view thereof.

In the drawings, 15 is a motor and 16 a

fan driven thereby, having its tangential outlet delivering to a suitable dust bag 17, and its eye communicating with an air passage 18 that merges flaringly into a main nozzle structure 19 of proper dimensions to receive the rotatable brush 20, which is driven from the motor, preferably by gear and shaft mechanism. The machine frame is preferably mounted on front rollers 21 and a rear caster 22, for easy propulsion by means of the handle 23 that is pivoted to the frame.

Preferably the wheels 21 support the main nozzle structure with the bottom edge of its end- and front-walls at a predetermined distance from the supporting plane of wheel-contact (i. e., more briefly, the work-plane), and preferably, also, such wheels are housed within the ends of the nozzle structure, only to project slightly therebelow. 70 Both fixed and adjustable positioning of the wheels in such relation being known in the art, I illustrate the wheels, for simplicity, as mounted on rigidly-positioned studs 24 secured directly in the end walls 25 of the nozzle portion of the main frame-member. 75 As to the brush structure, extending longitudinally of the nozzle 19 nearly from wheel to wheel (see Fig. 4) I provide a capacity for free or independent movement toward 80 and from the work-plane, and preferably give the brush 20 substantially a uniform bearing pressure on the work-surface over which it travels, so that the pressure may be at once lighter than and steadier than that 85 which would be imposed were the brush axis fixedly related to the wheel axis. And as to the nozzle, I preferably provide a sub-nozzle structure, including the parallel lips that co-act with the work,—that also may 90 move toward and from the work-surface, freely or independently of the main nozzle structure, and preferably along with the movements of the brush.

The fan 16 I prefer to mount in horizontal arrangement, with a vertical shaft so that the electric motor 15 may be mounted directly on the main frame above the fan chamber, and in using such construction I 100 preferably provide a vertical extension shaft 26, rotatively connected with the motor shaft and gear-driving a substantially horizontal shaft 27 which reaches forward, preferably below the air passage 18, into the nozzle structure, where it is gear-connected as by 105 110

- beveled gears 28, 29 with the spindle 30 of brush 20.
- In the specific construction shown whereby I provide for application of the brush to the supporting surface independently of the position of the supporting wheels or main frame, (and wherein I also attain many advantages of simplicity, manufacturing economy, ease of assembling and dismemberment, etc.) I preferably construct the body of the cleaner in two principal parts, namely a main frame structure 31, separately shown in Figs. 10 and 11, and a sub-frame structure 32, separately shown in Figs. 12 and 13. The brush 20, and its driving mechanism back to and including the shaft 26 I preferably mount in the sub-frame structure, and this sub-frame I pivotally mount in the main frame on a horizontal axis, as a desirable manner of giving said sub-frame for some capacity for vertical displacement of its brush-carrying end. In this arrangement I preferably locate the pivotal axis so that the brush-carrying or forward end of the sub-frame overbalances its rear end, thus lightly but firmly to bring the brush into contact with the supporting surface. As regards the brush, this provision of a sub-frame structure effectively provides one available arrangement, mounting the brush for movement independently of the main frame; and as regards the brush-operating mechanism the construction provides one convenient arrangement for assembly of the brush-drive mechanism on a demountable structure, facilitating sub-assembly and dismemberment, while as regards the frame structure generally the organization provides one effective arrangement of a removable bottom structure giving access to the interior of the machine and simplifying manufacture.
- Referring particularly to Figs. 10 and 11, the main frame is shown as providing a horizontal fan chamber 33, walled to afford the tangential outlet passage 34 and having at its bottom the eye 35, the rear end of the casting being worked out to symmetrical form by suitable extension walls 36. A skirt 37 on the under side of the fan chamber defines a portion of the air passage 18, merging into the nozzle-portion 19 of the main frame, so forming an open-bottomed shell.
- The sub-frame 32 provides a plate member 40 shaped conformably with the main body to fit in said shell and substantially to close the bottom of the air passage 18, and pivotally mounted in the main body as on the spring-pressed pivot pins 41 carried by the sub-frame and engaging openings 42 of the main frame. At the forward end of the sub-frame I provide what I may term the sub-nozzle, formed of lips 43, bounding at front and rear the orifice 44 through which the brush works, these lips being connected by end arches 45 and center arches 46, all of which are suitably shaped to act as guides and to receive in sliding, demountable engagement therewith the respective end bearing-blocks 47 and center bearing-blocks 48, which are fitted on the brush spindle 30.
- In the specific construction shown the brush unit 20 comprises the four bearing elements 47 and 48 for the spindle 30 and, upon the spindle and between the two central bearing members, the gear 29 is mounted. This unit is adapted to be slipped into or withdrawn from the arched guides and, when in place, may be suitably retained, as by a cover plate 50 (Fig. 12) a portion of which underlies the center bearings and their guide arches 48, and makes an impervious fit therewith.
- It will now be apparent that the sub-frame, having its forward end sufficiently shorter than the nozzle end of the main frame to clear the wheels 21 carried by the main frame, provides a sub-nozzle, and a rotatable brush constantly related thereto, the brush and sub-nozzle being freely movable, within limits, so as to take working position independently of the position of the main frame and the wheels.
- It is desirable to have the driving gearing for the brush completely enclosed, so that it may be grease-packed or otherwise suitably lubricated, and therefore I make the center guides 46 and the cover plate 50 portions of an enclosure for the brush-gear 29, this enclosure finding continuation through a shaft-box or channel 51 (for shaft 27) to a flat gear-box 52 at the rear portion of the sub-frame; the cover member 50, heretofore referred to, extending to cover the bottom opening of these several recesses. Shaft 27 may be mounted in bearing blocks 53, 53' of non-circular cross-section that, when removably slipped into the channel 51, will be retained by the cover plate. Shaft 27 carries a gear 54 through which it may receive motion from worm 55 on the vertical shaft 26, which, in turn, is driven from the fan shaft. To maintain this driving relation, while leaving the sub-frame free for its limited range of movement, I slidingly interfit the upper end 26' of shaft 26 with the fan hub, these interfitting parts being of non-circular cross-section. Shaft 26 may find bearing in a block 57 fitted in standard 58 of the subframe casting, and in a sleeve 59 fitted into the removable cover-plate 50, so that on detachment of the cover-plate the shaft 26 may readily be withdrawn.
- I prefer to make provision such that the positive driving of the brush from the fan shaft may be stopped at will, and to this end I arrange the gear 54 loosely on shaft 130

- 27 and provide a clutch, exteriorly operable, by which said gear may be secured for rotation to said shaft. The loosely mounted gear 54 has a cone-clutch extension 60, while 5 on the end of shaft 27 there is slidably but non-rotatably mounted a complementary clutch member 61 urged toward the cone by a spring 62 that surrounds the shaft and bears against an end washer 63. The angular groove of clutch member 61 is engaged by a shifter lever of bell-crank design, pivoted at 65 and having its extremity 66 (see Fig. 8) cam-beveled for coaction with a cam pin 67 suitably carried, in vertical position, by the sub-frame. In the 10 main frame another pin, 68, aligning with pin 67, forms in effect, a working extension of the first, this pin 68 being normally raised by spring 69 and provided with a latch head 15 70 which, when depressed, may be rotated by means of the handle piece 71 to throw the latch nose 72 under a suitable retaining stop, such as a marginal portion of the motor frame, thereby holding the aligning 20 pins down in such position that bell crank lever 64 is cammed over to disengage clutch member 61 from cone 60. A toe 23' on the foot of the pushing handle may depress the pin 68 whenever the handle is thrown forwardly far enough (preferably past dead center of the handle position). In general, 25 this provision for shifting the clutch corresponds with that disclosed in my co-pending application, Serial No. 455,010 filed 30 March 24, 1921 (now Patent No. 1,458,939, June 19, 1923), and further, my present preferred construction embodies a feature of a closing shutter 73 for the air passage 18, which is also disclosed in that application. 35 Such shutter is shown as pivoted on a cross-shaft 76, frictionally resisted in movement by action of a spring 77 but operable by a lever 78 (Fig. 6) which, when in shutter opened position, also retains in place the closure 79 for an attachment- 40 orifice 80. In respect of this last mentioned construction I prefer to arrange the shutter-pivot substantially directly over the pivotal axis 42 for the sub-frame, so that rocking 45 of the sub-frame within its rather small limit of permissive movement will have no appreciable effect upon the closing-action of the shutter.
- It will, of course, be understood that while 50 I have herein-described in some detail one particular embodiment of my invention for purposes of full disclosure, and may claim some of the detail provisions thereof for their specific advantages, that in its broader 55 aspects my invention is susceptible of embodiment in other forms and modified structures, all within the spirit of my invention and within the scope of the appended claims.
- I claim:
1. In a vacuum cleaner, having a main 60 nozzle-structure arranged at definite elevation above the work-plane, a sub-nozzle structure freely movable in the main nozzle toward and from said work-plane and unaffected by the weight of the main nozzle 70 structure.
2. In a vacuum cleaner, having a main nozzle-structure arranged at definite elevation above the work-plane, a sub-nozzle structure freely movable in the main nozzle 75 toward and from said work-plane, and a rotatable brush associated with the sub-nozzle for movement therewith to coact with the work free from the weight of the main nozzle-structure.
3. In a vacuum cleaner, a main frame including a main nozzle structure, a sub-frame, and a power-driven brush carried by said sub-frame, said sub-frame being freely movable to permit the brush to rise and fall 80 relative to the main frame and said sub-frame having sub-nozzle lips movable with the brush.
4. In a vacuum cleaner, a main frame providing a main nozzle structure, a sub-frame 90 extending within the nozzle and pivoted for free relative movement of its forward end with respect to the nozzle and at said forward end providing sub-nozzle lips; a brush mounted in said forward end of said sub-frame above and between said lips; and means to drive the brush in any position of the sub-frame.
5. In a vacuum cleaner, a main frame providing an open-bottomed shell including 100 nozzle portions, portions of the walls of an air passage, and a fan chamber; a sub-frame having a portion forming a wall arranged to substantially close the bottom of, and complete, said air passage and having also 105 a forward portion forming the rear lip of the nozzle structure, said sub-frame being mounted with respect to the main frame to permit free rise and fall of said nozzle-lip, a motor driven fan in said fan chamber; a 110 brush in the nozzle structure mounted on said sub-frame to rise and fall therewith; and driving connections between the fan motor and brush operable in any position of the brush.
6. In a vacuum cleaner, a main frame providing an open-bottomed shell including nozzle portions, a nozzle brush, a sub-frame carrying said brush, substantially closing the bottom of said shell in rear of said nozzle forming an air passage and mounted to permit free movement of the brush carrying portion of said sub-frame relative to the main frame, said sub-frame having an open-bottomed gear-casing shell formed thereon, a removable bottom closure for said gear-casing shell, a motor, brush-driving means 120 operated from said motor and including portions confined in said gear-casing shell.
7. In a vacuum cleaner, a main frame pro- 125

viding open-bottomed walls partly enclosing an air passage and a nozzle-portion, a nozzle brush, a sub-frame carrying said nozzle brush, providing a substantially closed gear-casing structure, and mounted in the main frame for rise and fall of its brush-carrying end independently of the main frame, said sub-frame completing said air passage, a motor, and motor-driven, brush-driving mechanism mounted in said gear-casing of the sub-frame.

8. In a vacuum cleaner, a main frame having a nozzle portion, a brush-unit arranged in said nozzle portion comprising a brush having a shaft and bearings therefor, a sub-frame having bottom openings to receive said bearings with the shaft therein, and mounted with respect to the main frame for free vertical movability of the brush independently of the main frame, and means to detachably retain the bearings in the sub-frame.

9. In a vacuum cleaner, a main frame providing a main nozzle structure, a nozzle brush, a sub-frame carrying said nozzle brush and mounted in the main frame to permit vertical movement of said nozzle brush independently of the main frame, means to drive said brush including a motor, and a horizontal shaft connected to be driven by the motor and to drive the brush, bearings for said shaft, said sub-frame being provided with bottom openings to receive said bearings, and means for demountably retaining said bearings in said openings.

10. In a vacuum cleaner, a main frame provided with a main nozzle portion, a horizontal fan casing, and walls forming the open-bottomed shell of a connecting air passage, a sub-frame detachably mounted to close the bottom of said air passage and to permit free vertical movement of the forward extremity of said sub-frame, and a power-driven brush carried by the forward end of said sub-frame.

11. In a vacuum cleaner, a main frame providing a main nozzle structure and open-bottomed walls of an air passage, and a fan casing, of a sub-frame detachably mounted in said main frame to permit vertical move-

ment of the forward extremity of said sub-frame independently of the main frame and substantially to close the bottom of said air passage, said sub-frame being provided with a nozzle-lip.

12. In a vacuum cleaner, a main frame providing a main nozzle structure and open-bottomed walls of an air passage, and a fan casing, of a sub-frame detachably mounted in said main frame to permit vertical movement of the forward extremity of said sub-frame independently of the main frame and substantially to close the bottom of said air passage, said sub-frame being provided with a sub-nozzle structure affording front and rear nozzle lips.

13. In a vacuum cleaner, a main frame providing a horizontal fan casing, an open-bottomed air passage structure, and a nozzle structure, a fan in said casing, a driving motor for the fan, a sub-frame structure pivoted to the main frame, a brush carried by the forward portion of said sub-frame, driving gearing for the brush carried by said sub-frame and including a vertical shaft, and an axially slidably, non-rotatable connection between said vertical shaft and the motor shaft.

14. In a vacuum cleaner, a main frame providing a nozzle portion, a sub-frame pivoted to the main frame and carrying a brush disposed in the nozzle of the main frame, driving gearing for said brush mounted on said sub-frame and including a disconnecting clutch, clutch-disengaging means carried by said sub-frame, and means for operating said clutch-disengaging means carried by the main frame.

15. In a vacuum cleaner, the combination of a main frame providing a nozzle portion and an open-bottomed air passage portion, a sub-frame horizontally pivoted in the main frame and substantially closing the open bottom of the air passage, and a shutter for interiorly closing the air passage horizontally pivoted in substantially the vertical plane of the pivotal axis of said sub-frame.

JOHN T. HUME.
